UNITED STATES PATENT OFFICE.

HILARIO DE ESCOBALES, OF STATEN ISLAND, NEW YORK, ASSIGNOR TO H. ESCOBALES CO., INC., OF NEW YORK, N. Y., A CORPORATION OF NEW YORK.

WRAPPING MACHINE.

Application filed October 11, 1918. Serial No. 257,708.

To all whom it may concern:

Be it known that HILARIO DE ESCOBALES, a citizen of the United States, residing at Staten Island, in the county of Richmond 5 and State of New York, have invented new and useful Improvements in Wrapping Machines, of which the following is a specification.

This invention relates to improvements 10 in wrapping machines, pertaining more particularly to machines adapted to apply a wrapping element to a packet or charge.

The general objects of the invention are 15 to provide a machine of simple construction and formation adapted to apply the wrapper in adhesive connection to the packet in a simple and efficient manner to produce a package completely enclosed by the wrapper with the wrapping so arranged 20 as to provide practically a sealed package.

While the machine is operative in the production of packages containing commodities of various types, it is especially adapted for use in the production of packages 25 containing tobacco products, as for instance, smoking tobacco. The packaging of commodities of this type necessarily presents inherent difficulties, by reason of the fact that it is practically essential that the 30 characteristics of the product be maintained as far as possible, especially during the period intervening between the packaging operation and the time when the package is opened for use. This period is 35 more or less indefinite and it is therefore desirable that the enclosure be such as will reduce liability of deterioration as far as possible.

Packages for this purpose have heretofore 40 been produced but these generally depend upon the inner wrapping as the deterioration-preventative, the outer wrapper being more or less of label form designed mainly as a protection for the tin foil inner wrapping structure. In providing such outer wrapping or label it is the general 45 practice to maintain one end of the package—the end to be opened—free from label closing, due mainly to the difficulty of producing a label construction which will pro-

vide the sealed formation in a simple manner, without the use of a complicated blank, the use of complicated mechanism, and under high capacity conditions, it being understood of course that the packaging operation must be provided at a minimum cost of production in order that the sale price of the package will not be excessive.

Another factor involved is brought about by the difficulty of utilizing tin foil for 55 packaging purposes, the scarcity of this material under the present conditions of warfare, making it desirable to provide a package structure in which the foil construction may be omitted without materially affecting 60 the integrity of the package as to the characteristics of the commodity.

These difficulties are solved in the production of a package in which the deterrent features are more particularly embodied in 65 the outer or label wrapping, by producing such wrapping in a form which will provide 70 these results.

The particular form of package is not claimed herein, the present invention pertaining to a type of machine or apparatus 75 adapted to produce wrappings of this kind generally, the machine being designed to meet the inherent problems present in attempting to produce a package of this kind 80 in a simple and efficient manner and under high capacity conditions.

Other objects reside in the detailed construction of the different instrumentalities employed and their general arrangement 85 for mutual and combined operation in the production of the package.

To these and other ends, the nature of which will be readily understood as the invention is hereinafter disclosed, said invention 90 consists in the improved construction and arrangement of parts hereinafter fully described, illustrated in the accompanying drawings, and more particularly pointed out in the appended claims.

In the accompanying drawings, in which similar reference characters indicate similar parts in each of the views,—

Figure 1 is a view in side elevation, with parts broken away, showing one embodi- 100

ment of invention adapted to practice the present invention.

Fig. 2 is a top plan view, with parts broken away and omitted for clearness.

5 Fig. 3 is an end elevation.

Fig. 4 is a detail sectional view showing the upper folding channel.

Fig. 5 is a similar view of the lower folding channel.

10 Figs. 6 and 7 are diagrammatic sectional views illustrating details of operation of the folding devices.

Fig. 6^a is a face view of the first plunger.

Fig. 8 is perspective view indicating 15 the manner in which the packet and wrapper are brought into assembly relation.

Figs. 9 to 13 are similar views indicating steps in the formation of the package.

Fig. 14 is a perspective view of the completed package.

Before describing the mechanism and instrumentalities of the machine in detail, I will briefly describe the form of package produced and the general operation employed 25 in such production, although it will be readily understood that the invention is not limited in its application to the production of the particular package described.

As shown in Fig. 8, the packet or embryo 30 package E is shown as in the form of a wrapped packet, a simple wrapping being applied about the commodity, the packet being, in the present instance, produced on a different machine and being of a form heretofore provided in connection with tin foil packages, a 35 form which can be utilized in the present invention but which can be changed to a simple paper wrapping by substituting a heavier sheet of paper for the composite tinner foil sheet heretofore employed. This packet is introduced into the machine in suitable manner—shown as in the form of an endless belt conveyor—and brought to a stop in alinement with an upper folding channel 40 and in advance of a plunger.

The wrapping element W is shown as in 45 the form of a blank, generally rectangular and having a length greater than the peripheral length of the walls of the package 50 on a longitudinal section of the packet, and having a width sufficiently greater than the width of the packet to provide marginal portions utilized in the productions of wings or wing formations presently described; the 55 blank also preferably carries a projecting tongue w although this is not absolutely essential, and the body of the wrapper may have a weakened line structure—indicated at w—for a purpose presently described. 60 The blank also carries a plurality of adhesive stripes w² extending in the direction of length of the blank—four stripes extending in parallelism being shown, two adjacent the opposite marginal edges, and two spaced 65 therefrom a distance such as to place them

within the width of the packet; in other words, the inside stripes are spaced apart a distance less than the width of the packet to provide an adhesive connection between the element and the packet as the folding operations take place. While I have referred to the use of spaced stripes, I may obviously increase the number of stripes or zones of adhesive even to a point where the blank may be substantially coated; I prefer however, to 70 employ the striping referred to.

The blanks are fed successively into position between a positioned packet E and the entrance to the first folding channel, being supplied by a suitable feeding mechanism 80 such, for instance, as is disclosed in my companion application filed March 13, 1917, Serial No. 154,447, this feeding mechanism being adapted to deliver the blanks individually from a stack of blanks to the desired point with respect to the packet and the first or upper folding channel, the blank receiving the stripes of adhesive during travel to such point, the delivered blank extending in a vertical plane and positioned 85 relative to the packet approximately as shown in Fig. 8 but out of contact with the packet.

With the packet and blank in these relative positions the plunger advances into contact with the rear end of the packet and advances the latter into contact with the wrapping element to produce an assembly of these elements; as the adhesive stripes of the positioned blank are on the rear face of the blank, this action brings the advance end of the packet—which forms the bottom of the complete package—into contact with the inner stripes of adhesive and tends to adhesively connect the packet and wrapper. 90 As the plunger advances this assembly is carried into the first—the upper—folding channel which folds blank portions into contact with the opposite side faces of the packet, and then tucks in the marginal portions which project at the sides of the advance end, as at w³, the result of these operations being shown in Fig. 9. This adhesively connects the opposite side faces of the packet to the wrapper through the inner adhesive stripes, so that the wrapper is firmly secured to these faces of the packet, while the tucked-in portions w³ are adhesively secured to the side edges of the packet. The relative positions of wrapper and packet in 95 the assembly are preferably such that the upper edge of the wrapper in Fig. 8 will, on the completion of the operations just described, extend practically to the rear end of the upper face of the packet, although this may be varied if desired.

Before leaving the first channel, wings w⁴ produced during these described operations, are folded downward into contact with the edge walls of the packet and in overlying re- 100

lation to the tucked-in portions w^3 , producing the formation shown in Fig. 10, thus securing these wings to the packet by the adhesive stripe portions carried by these wings, 5 the stripes of the wings extending longitudinally of the packet, while those of portions of w^3 extend transverse of such length.

As the plunger continues its advance this assembly formation is carried into a vertically-movable carrier a distance sufficient to cause the rear end of the packet to clear the discharge end of the folding channel, the trailing portion of the blank—which is of greater length than the width of the rear 15 end of the packet—remaining in the folding channel. This completes the advancing movement of this plunger which then retreats to its initial position.

After the assembly is thus positioned, the 20 vertically movable carrier is shifted downward, withdrawing the trailing end of the blank from the first folding channel and folding this portion of the blank into up-standing position, as in Fig. 11, thus covering 25 the remaining end of the packet, as at w^5 , and where the packet end is flat, adhesively connecting the blank to such end of the packet by the inner adhesive stripes. This end w^5 forms that end of the complete 30 package which is to be opened in use.

The downward movement of the carrier brings it opposite the open end of a second folding channel, the entrance to this channel being directly in front of end w^5 , this movement locating the carrier between the entrance to the channel and a second plunger, the latter—at this time—being opposite the bottom of the package, the end which formed the advance end of the assembly while traveling through the first channel.

When the carrier reaches this position, the second plunger is advanced into contact with the bottom of the package and begins to move the assembly formation of Fig. 11 out 45 of the carrier in a direction opposite that of the advancing movement provided by the first plunger, the result being that end w^5 now becomes the advance end of the assembly. This advancing movement enters the assembly advance end into the second channel, the first result being to fold the upstanding portion of the blank on to the top of the packet, as at w^6 , adhesively securing such portion to the wrapper portions which had 50 been previously secured to the upper face of the packet, after which the projecting marginal portions at the ends of face w^6 are tucked in, as at w^7 , producing the lower wings w^8 , and upper wings w^9 , as in Fig. 12, 55 wings w^9 being formed by the projecting marginal portions of the upstanding part of the blank in Fig. 11.

As the plunger continues its advancing movement, wings w^9 are turned down into contact with tucks w^7 and previously folded

down wings w^4 —Fig. 13—and adhesively secured thereto, this folding being followed by the upward folding of wings w^8 into overlying relation to wings w^9 and w^4 , completing the folding operations and producing 70 the package shown in Fig. 14, folding of wings w^8 adhesively securing them to the down-folded wings.

As will be understood from Figs. 8 and 12, the presence of the outer stripes of adhesive provides adhesive connection of the various folds and tucks, the securing lines extending angularly to each other, so that there is presented a barrier—in the form of an adhesive connection at all points where the marginal edges of the blank are located, closing the folded edge portions of the package against the passage of air or moisture. Owing to the absence of transverse lines of adhesive, this barrier is absent at the point 80 where the ends of the wrapper are located, but this is compensated by the fact that portion w^6 is drawn into and held in close contact with the upper face of the applied wrapper end by the particular folding operations, and the length of this wrapper portion is such as to practically eliminate liability of difficulty at this point.

This leaves the major part of portion w^6 95 free to be torn off by grasping tongue w and pulling toward end w^5 —weakened line w' facilitating this action where employed—and since the end w^5 is also free from adhesive connection—excepting possibly at the opposite edges—this operation practically 100 opens the end of the package, the lower wall of the packet at end w^5 in Fig. 14, forming a guide or tearing edge which permits the end w^5 to be torn off and maintain a neat appearance of the package.

As will be understood the general success of the package in excluding air and moisture is practically dependent upon the presence of the lines of adhesive at the points shown and in the proper folding of the wrapper into the desired formation. To obtain these results in large capacity operations forms problems of the machine construction, in that provision must be made for striping the wrapper with the adhesive on predetermined lines in advance of folding operations, the production of the folds in the proper manner while operating with blanks carrying adhesive stripes, and the completion of the folding operations in advance of drying 110 of the adhesive in order that assurance is had that the final folds will provide a proper adhesive connection.

In describing the embodiment of the invention which I have utilized for the purpose of explaining the general features of the invention, I follow, as far as possible, the order of operation above described.

20 designates a frame of suitable character on which the operating parts are mount- 120

ed and which includes the opposite side frame members 20^a and 20^b, suitably braced. This frame carries the drive shaft 21, driven from any suitable source—indicated by the usual fast and loose pulley combination 22.

Referring first to the introduction of the packets, 23 indicates an endless conveyor having the direction of its travel transverse to the direction of length of the frame. The conveyor extends outward beyond side frame 20^a (Fig. 2), a rotatable support, such for instance as a pulley 24, being provided within the machine proper between the opposite side frames and preferably located adjacent to and parallel with frame 20^b. Conveyor 23 may be operated in any desired manner, the form shown in the drawings being by connecting pulley 24 to drive shaft 21, thus synchronizing the movements of the conveyor with those of the remaining portions of the apparatus. This connection is had by operatively connecting the shaft of pulley 24 with a shaft 25 by means of a vertical shaft 26, these shafts being operatively connected by suitable bevel gear connections, these shafts being supported by the frame or by brackets in a convenient manner. Shaft 25 extends parallel with drive shaft 21 and is driven therefrom by gear connection 27, 28.

The upper or active flight of the conveyor 23 travels in the direction of the arrow in Fig. 2 and extends past the longitudinal centre line of the machine and beneath a suitable strip or bar 29 carried by and depending from a plate 30 supported by a brace 31 extending between the side frames, said plate 30 extending over the flight and being spaced therefrom a distance to permit the free entrance of a packet beneath the plate, strip or bar 29 forming a stop in the path of movement or travel of a packet, this stop being located to properly position the package relative to the first folding channel and the plunger operative therein, the conveyor flight being operative between these elements.

The packets are placed on the conveyor automatically or manually by an attendant, and the advance of the flight locates the packets successively in contact with stop 29, the packets being positioned on the conveyor to cause the packet ends to oppose the folding channel and plunger when in contact with the stop. As the conveyor is preferably continuously movable, the packets may be collected or assembled in a row with the advance packet in contact with the stop—the conveyor simply slipping by the positioned packets—advance of the plunger removing the advance packet and retaining the row in position until the plunger returns to its inactive position to permit advance of the row to position the succeeding packet in contact with the stop.

The blanks may be introduced in any suitable manner, a simple blank feed instrumentality being indicated in the drawings based more or less on the general construction shown in the companion application heretofore referred to. This instrumentality includes a table 32 for a stack of blanks, this table being supported by standards 33 and posts 34, and provided with suitable guides for retaining the blanks in proper alignment. The blanks are fed from the bottom of the stack by a reciprocating element, indicated generally at 35, and which includes rolls and bands adapted to advance the lowermost blank by frictional engagement therewith during advancing movements of the element and run free on the return movement of said element. Element 35 is reciprocated by a pitman connection with a shaft 36, the latter being geared to a shaft 37 operatively connected with shaft 25 through a vertical shaft 38, bevel gears being employed to provide the connection between shafts 25 and 38 and the latter shaft and shaft 37. If it be desired that shaft 37 have a periodic movement, the gear connection between that shaft and shaft 38 may be in the form of the usual mutilated gears.

Shaft 36 carries roll 39 which extends to the plane of the advancing blank, said roll carrying a plurality of bands 40—which may be in the form of endless coil springs—these bands extending over an idler roll 41 mounted between standards 33 at a suitable distance below roll 39. Shaft 37 also carries band-carrying roll 42, the bands of which extend over an idler 43 opposing idler 41 and over an idler 44 located above roll 39, idler 44 and roll 39 and the bands mounted thereon forming a throat into which the blank is delivered into the band-formed flight provided by the opposed strands of bands, this flight acting to shift the travel of the blank from a horizontal plane to a vertical plane.

Mounted below roll 39 is an adhesive applying mechanism of suitable type, this mechanism including a plurality of disk rolls 45 properly spaced to provide the stripes w^2 , the disks having their peripheries extending into a position of contact with a blank as it is fed downward by the band-formed flight, the bands being suitably spaced to permit this adhesive application. This mechanism may be driven in any suitable manner as by a chain connection with shaft 36.

As will be readily understood each advance movement of element 35 introduces a blank into the band-formed flight in which it is carried past the adhesive applying rolls and provided with stripes w^2 , the flight feeding the blank downward with the blank extending flatwise in a vertical plane. The parts are so positioned and operated that

the advancing blank passes downward between the plane of the end of a packet and the entrance to the first folding channel with the stripes w^2 facing the end of the packet.

5 Since it is desired that a particular portion of the blank be opposite the packet end when the blank and packet are brought into contact, I prefer to provide a suitable stop or support 46 for the lower edge of the

10 blank and release the blank from the flight just prior to reaching the support in order that the blank may readily drop to position, the lower end of the flight being positioned for the purpose.

15 Since it is necessary only that the packet and blank be in proper position when the first plunger begins its advancing movement, it will be readily understood that the

20 positioning movements of these package elements can be provided at any time when the plunger is out of the path of travel of the elements in reaching their positions. With these elements in position the plunger begins its advancing movement, the

25 particular formation of plunger and form of operating mechanism therefor illustrated being one embodiment which may be employed.

As indicated in Fig. 2, 47 indicates a guide carried by side frame 20^b and within which is mounted a slide 48, said slide being formed with a rack face adapted to co-operate with a toothed wheel or segment 49 mounted on a shaft 50. Said shaft is given an oscillatory motion from shaft 25 by suitable connections, the particular embodiment utilized in the drawings being now described:

Shaft 50 carries a pinion 51 meshing with a gear wheel 52 mounted on a shaft 53 located below shaft 50, said shaft 53 also carrying a pinion 54 in mesh with a gear segment 55 mounted loosely on shaft 50 (Fig. 1). Obviously, oscillation of segment 55 will, through connections described, operate to oscillate shaft 50 and its toothed wheel or segment 49 to reciprocate the slide 48 in guide 47.

Mounted on shaft 25 is a face cam 56 the groove of which is adapted to receive a roller 57 carried on a bar or pitman 58, one end of which is slotted to straddle shaft 25, the opposite end being pivoted to segment 55. Rotation of cam 56 causes pitman 58 to be advanced and retracted, this motion providing the oscillating movements to segment 55.

Extending longitudinally of the machine is a plunger support or guide 59 mounted in suitable brackets projecting from side frame 20^b, said guide supporting plunger 60, the latter being located in alinement with the first folding channel, the plunger stem being in the form of a slide adapted to be reciprocated on guide 59 and being connected to slide 48 by a plate or other connection 61,

Plunger 60 may be of any desired construction, the form shown comprising a head 60^a located at the advance end of the plunger, and a stem 60^b extending rearwardly therefrom, and preferably a sheath-like member 60^c—approximately of inverted U-shape section—overlying the stem, said member constituting a device for preventing advance of a row of packets during the period when the plunger is advancing the

70 packet through the first folding channel, and hence having a length sufficient to provide a barrier against the advance of packets on conveyor 23.

The first folding channel 62 is of suitable form, that shown comprising upper and lower plates 62^a, end tuck faces 62^b and channels 62^c adapted to turn down wings w^4 as the assembly is advanced by the plunger, the movement of the latter first bringing the advance end of the packet into contact with the striped face of the positioned blank and then carrying the assembly into the folding channel, the successive action of plates 62^a and faces 62^b producing

80

85

90

95

the formation shown in Fig. 9, this being followed by the action of channels 62^c to produce the formation of Fig. 10, barrier 60^c preventing advance of the succeeding packet during this operation.

Operative at the discharge end of channel 62 is a vertically reciprocating carrier indicated generally at 63 and presently described, this carrier having a form to provide an assembly-receiving space which, as the assembly is advancing, is located in alinement with the channel, so that as plunger 60 continues its advancing movement the assembly is advanced into a position within said space, the trailing portion of the blank remaining in the channel, the carrier being formed to receive the blank marginal portions which produce wings w^8 without folding. This positioning of the assembly completes the advancing movement of plunger 60 which then returns to its initial position, freeing the row of packets and permitting the succeeding packet to advance to position for the formation of the succeeding assembly.

As shown in Fig. 3 the carrier is of a skeleton type comprising a frame formed with upper and lower cross-heads 64 and 65 connected by rods 66 mounted to reciprocate vertically in brackets 67 projecting from the side frames 20^a and 20^b. This frame is reciprocated vertically by the action of a cam 68 mounted on shaft 25 through suitable connections, one form of which will now be described:

69 designates a bifurcated lug depending from lower cross head 65 and to which is pivotally secured a link 70, the opposite end of which is secured to the bifurcated end of a lever 71 pivotally mounted on a suitable

125

130

rod or support forming a part of the general framework. Pivotedly connected to an intermediate portion of lever 71 is a rod or pitman 72 which extends upwardly, being provided with a slot 72^a through which shaft 25 extends, thus causing the pitman to straddle said shaft. The upper end of the pitman carries a roller adapted to cooperate with cam 68. As the cam rotates, its groove 10 causes lever 71 to be oscillated, such oscillations causing the carrier frame to be reciprocated in brackets 67, the particular arrangement of the frame leaving an open space approximately on the center line of the machine. Adjustably mounted on rods 66 15 are a pair of plate members 73 extending inwardly from the opposite sides of the frame, said members extending in the same horizontal plane and forming the bottom of 20 the space within which the structure of Fig. 10 is introduced, the inwardly projecting length of said members being such as to provide a space therebetween at approximately 25 the center line of the machine.

25 The carrier is completed by a positioning element secured to the upper cross head 64, said element comprising a plate 74 carrying a pair of depending bars or plates 74^a spaced apart a distance to permit the folded configuration of Fig. 10 to extend therebetween—bars 74^a serving to retain the folded condition of the structure, the lower faces 30 of the bars being spaced from members 73 to permit the unfolded marginal edges of the 35 blank to pass without folding action.

40 As will be understood this general arrangement of the carrier is such as to permit of adjustments and use of interchangeable positioning elements of different sizes, thus 45 providing for variations in size of the packet and package, the folding channels being of such formation as to permit change by substitution or adjustment to meet the changed conditions provided by variations in size.

50 The length of the reciprocating stroke of the carrier is such as to locate members 73 in substantial alinement with the bottom of the upper folding channel at the upper extreme of the stroke and in substantial alinement with the bottom of the second folding channel—presently described—at the lower extreme of the stroke, the cam groove being arranged to provide the proper extent of movement at the proper times, the general 55 adjustment of the carrier permitting an accurate location of members at the proper points.

60 The downward movement of the carrier not only serves to shift the assembly into a lower plane but also provides one of the folding steps, in that such movement is relative to the discharge end of the upper folding channel. Hence, when the carrier begins 65 its downward travel the trailing portion of 70 the blank shown in Fig. 10 is withdrawn

from the channel and folded into the upstanding position of Fig. 11 by the co-operation of the descending assembly and the stationary lower edge of the upper folding channel, the result being that when the carrier reaches its lower position the assembly will have the general formation shown in Fig. 11.

70 The lower folding channel is shown as formed in two sections 75 and 76 extending 75 in horizontal alinement and parallel to and below the upper channel, thus locating both channels on the same side of the carrier. Section 75 is preferably substantially similar in construction to upper folding channel 62, having the tuck-in faces 75^a and folding channels 75^b being operative to produce substantially the same successive stage actions as the upper channel, but being active on the unfolded end of the assembly—the rear portion of the latter during travel through channel 62—so that when the assembly is advanced from its position in the carrier—to 80 ward the left in Fig. 1—similar folding action on the upstanding portion of the wrapper shown in Fig. 11 will be had as was given the wrapper in passing through channel 62, successively producing the formations shown in Figs. 12 and 13. As will be seen 85 this arrangement causes the advance end to be transferred from one end of the packet to the other without reversing the assembly.

90 The second section 76 extends in alinement with the first section but is spaced therefrom to provide a space in which the lower end of the blank W may extend when introduced into the machine, thus permitting the stroke of the carrier to be reduced to a minimum and yet permit the use of the relatively long wrapper blank. Section 76 is 95 designed to provide the final folding—the upturning of wing w^a—and is therefore provided with suitable folding edges 76^a which provide this result.

100 The advancing movements of the assembly from the carrier are provided by a plunger 77 normally located on the opposite side of the carrier from the folding channels, said plunger 77 being of any desired construction, that shown being substantially similar to plunger 60 with the possible exception that barrier 60^c may be omitted. The mechanism for operating plunger 77 is substantially similar to that for plunger 60, a separate cam 78 being utilized and the guide being secured to side frame 20^a. The length of throw of plunger 77 may be similar to or slightly less than that of plunger 60, it being understood that it is necessary 110 only that the advancing movement of plunger 77 be sufficient to carry the assembly beyond the folding edges 76^a, further movement of the assembly being provided by the succeeding assembly delivered by the next 115 advance of the plunger 77. The length of 120

125

section 76 is therefore not dependent upon the length of throw of plunger 77 and may therefore be of any desired length, thus providing an arrangement in which the complete assembly shown in Fig. 14 may be held in proper position and formation until the adhesive has properly set, the assembly being discharged from the discharge end of section 76 into a suitable receptacle or a conveyor not shown.

It will be understood, of course, that the various operations are so timed as to prevent interference of mechanisms and produce the successive operations in proper manner. In this connection it will be understood that the requirement of complete folding action in advance of the actual setting of the adhesive is one of the factors controlling the time and also the general arrangement of the machine, this being one of the problems inherent in the production of an apparatus for the present purpose, it being understood that the inherent difficulties provide a time factor of material importance.

In this connection, the formation of the second folding channel in two sections is of importance in that it permits the wrapper to be properly positioned without requiring an excessive length of stroke of carrier 63.

In addition, the cam timing may be so arranged as to reduce the operating time of travel of the assembly to a minimum, Figs. 6 and 7 indicating one way in which this can be provided in that the advancing movements of the plungers can be timed so that the advance end of the assembly in the second folding channel will miss the lower end of the blank being drawn by the advance movement of the packet in the upper folding channel, as shown in Fig. 6. By comparing Figs. 6 and 7, an operation under maximum speed conditions is shown, Fig. 7 indicating the position of parts at the time when the packet is brought into contact with the blank by the advance of plunger 60, plunger 77 having advanced the assembly from the carrier into the second folding channel, while the previously completed package is located in the second section of the latter folding channel. In Fig. 6 the plungers are shown as further advanced. As will be seen by comparing these views, carrier 63 is shifted from its lower to its upper position during the time between the passage of the assembly and the head of plunger 77 from the carrier and the advance of the assembly in the upper channel to a point where the advance end of such upper assembly is approaching the discharge end of the upper channel. This shifting in position of the carrier within the small space of time is permitted by reason of the relatively short stroke of the carrier and the presence of the space between plate members 73, this space permitting the assembly sup-

porting surface—members 73—to move upward without being affected by the presence of the stem of plunger 77 which is advancing at this time. Since the reciprocating movements of the plungers are controlled by cam action, it will be understood that each plunger may be retracted at a rapid speed—these movements being independent of assembly movements and therefore not hampered by the inherent difficulties of operation with paper blanks—so that both plungers will be in proper positions to permit the location of the downwardly moving structures which cross the paths of these plungers—the wrapper blank with respect to plungers 60 and the carrier in connection with plunger 77.

Another factor in the ability to provide the complete operation of wrapping before setting of the adhesive is the fact that the general manner of wrapping and the successive operations are such as will permit of the use of relatively short folding channels, thus decreasing the throw of the plungers, so that the complete folding action can be had in a comparatively short space of time, with the time of action on succeeding assemblies reduced to a minimum, thus additionally providing for high capacity conditions.

As will be understood, a variation in the form of the package wrapping can be readily provided by reversing the direction of channels 75^b and folding edges 76^a. With this change wings w^8 will be folded into overlying relation to wings w^4 , wings w^9 then being folded on to folded wings w^8 and locating wings w^9 as the overlying wings of the wrapping instead of being in underlying relation to wings w^8 . I prefer, however, to employ the arrangement shown.

While I have herein shown a preferred embodiment of the invention, it will be readily understood that various changes and modifications therein may be found desirable or essential in meeting the various exigencies of use, and I desire to be understood as reserving the right to make any and all such changes or modifications as may be found desirable or necessary in so far as the same may fall within the spirit and scope of the invention as expressed in the accompanying claims when broadly construed.

Having thus described my invention, what I claim as new is:

1. In wrapping machines, wrapper-folding instrumentalities operative on an assembly of packet and wrapping blank to apply the blank to substantially the entire area of the packet by advancing movements of the assembly, said instrumentalities including upper and lower folding channels extending in parallelism, each channel operative to apply predetermined portions of the blank and both operative to apply the blank to

2. In wrapping machines, wrapper-folding instrumentalities operative on an assembly of packet and wrapping blank to apply the blank to substantially the entire area of the packet by advancing movements of the assembly, said instrumentalities including upper and lower folding channels extending in parallelism, plunger means for and operative to advance the assembly within the several channels, and a vertically reciprocating carrier operative in the transfer of the assembly from the upper to the lower channel, said upper channel being operative to provide the assembly with marginal portions of the blank projecting beyond the packet side faces in the plane of the blank, said carrier having an assembly support and a positioning device relatively positioned to preserve the positions of these marginal portions during transfer of the assembly.

the blank to the several faces of the packet by advancing movements of the assembly, said instrumentalities including upper and lower folding channels extending in parallelism, plunger means for and operative to advance the assembly within the several channels, and a vertically reciprocating carrier operative in the transfer of the assembly from the upper to the lower channel, said carrier being positionable in the path of movement of the lower channel plunger to permit discharge of the assembly from the carrier into the lower channel, said carrier including a reciprocating frame, members carried by said frame for supporting the assembly, said members being spaced apart in the plane of the plunger stem, and a positioning device carried by said frame above said members to maintain the position of the assembly within the carrier.

3. In wrapping machines, wrapper-folding instrumentalities operative on an assembly of packet and wrapping blank to apply the blank to the several faces of the packet by advancing movements of the assembly, said instrumentalities including upper and lower folding channels extending in parallelism, plunger means for and operative to advance the assembly within the several channels, and a vertically reciprocating carrier operative in the transfer of the assembly from the upper to the lower channel, said carrier being positionable in the path of movement of the lower channel plunger to permit discharge of the assembly from the carrier into the lower channel, and also having means to permit shifting of the carrier from such position when the plunger is out of its inactive position.

6. In wrapping machines, wrapper-folding instrumentalities operative on an assembly of packet and wrapping blank to apply the blank to the several faces of the packet by advancing movements of the assembly, said instrumentalities including upper and lower folding channels extending in parallelism, plunger means for and operative to advance the assembly within the several channels, and a vertically reciprocating carrier operative in the transfer of the assembly from the upper to the lower channel, said carrier being positionable in the path of movement of the lower channel plunger to permit discharge of the assembly from the carrier into the lower channel, said carrier including a reciprocating frame, members carried by said frame for supporting the assembly, said members being spaced

4. In wrapping machines, wrapper - folding instrumentalities operative on an assembly of packet and wrapping blank to apply the blank to the several faces of the packet by advancing movements of the assembly, said instrumentalities including upper and lower folding channels extending in parallelism, plunger means for and operative to advance the assembly within the several channels, and a vertically reciprocating carrier operative in the transfer of the assembly from the upper to the lower channel in the plane of the plunger stem, and a positioning device carried by said frame above said members to maintain the position of the assembly within the carrier, said device comprising a plate and elements depending therefrom and spaced apart to permit free entry of the assembly therebetween while maintaining the folds provided by the upper channel.

5. In wrapping machines adapted to enclose a packet within an adhesively-prepared wrapping blank having a width greater

- than the peripheral length of the packet on a section thereof, and wherein opposite ends of the blank extend in overlying relation on the same face of the packet with marginal portions of the blank completing the packet enclosure, wrapping instrumentalities for folding the blank into its enclosing position, said instrumentalities including a pair of parallel folding channels through 5 which the assembly is successively passed, and a reciprocating carrier operative in the transfer of the assembly from one channel to the other, said channels including means operative to fold marginal portions into 10 wings foldable into overlying relation on packet faces at the sides of said channels, the wing formations at opposite ends of the blank being produced and folded in different channels.
- 20 8. In wrapping machines adapted to enclose a packet within an adhesively-prepared wrapping blank having a width greater than the peripheral length of the packet on a section thereof, and wherein 25 opposite ends of the blank extend in overlying relation on the same face of the packet with marginal portions of the blank completing the packet enclosure, wrapping instrumentalities for folding the blank into its enclosing position, said instrumentalities including a pair of parallel folding channels through which the assembly is successively passed, and a reciprocating carrier operative in the transfer of the assembly 30 from one channel to the other, said channels being operative to fold marginal portions into wings foldable into overlying relation on packet faces, the wing formations of one end of the blank being folded 35 into contact with the packet in advance of the production of the wing at the other end of the blank.
- 40 9. In wrapping machines adapted to enclose a packet within an adhesively-prepared wrapping blank having a width greater than the peripheral length of the packet on a section thereof, and wherein 45 opposite ends of the blank extend in overlying relation on the same face of the packet with marginal portions of the blank completing the packet enclosure, wrapping instrumentalities for folding the blank into its enclosing position, said instrumentalities including a pair of parallel folding channels through which the assembly is successively passed, and a reciprocating carrier operative in the transfer of the assembly 50 from one channel to the other, said channels being operative to fold marginal portions into wings foldable into overlying relation on packet faces, the wing formation of one end of the blank being folded 55 into contact with the packet in advance of the production of the wing at the other end of the blank.
- 60 10. In wrapping machines adapted to enclose a packet within an adhesively-prepared wrapping blank having a width greater than the peripheral length of the packet on a section thereof, and wherein 65 opposite ends of the blank extend in overlying relation on the same face of the packet with marginal portions of the blank completing the packet enclosure, wrapping instrumentalities for folding the blank into its enclosing position, said instrumentalities including a pair of parallel folding channels through which the assembly is successively passed, and a reciprocating carrier operative in the transfer of the assembly 70 from one channel to the other, said channels being operative to fold marginal portions into wings foldable into overlying relation on packet faces, the wing formations of one end of the blank being folded 75 into contact with the packet in advance of the production of the wing at the other end of the blank.
- 80 11. In wrapping machines, a wrapping instrumentality for applying a wrapper to a packet during advancing movements of an assembly of these elements, said instrumentality including folding channels operative successively on the assembly, a plunger for and operative within each channel, and independent means for operating said plungers, said means including a slide extending parallel with a plunger, connections between the slide and plunger, a drive shaft located between the plungers, cams on said drive shaft, each of the cams controlling the movements of a slide, and 85 operating connections between a cam and the slide controlled thereby.
- 90 12. In a wrapping machine, a plurality of channels, means for conveying an assembled package and wrapper through the first channel, a plunger for conveying the assembly through the second channel, a reciprocating carrier adapted to receive the assembly from the first channel and shift it into alignment with said plunger and second channel, means for reciprocating said carrier adapted to return it from operative position adjacent to the second carrier to operative position adjacent to the first carrier prior to the retraction of said plunger into 95 position to engage an assembly presented by the carrier, and means operative on the assembly between the entrance to the first channel and the exit from the second channel, for folding the wrapper flatwise 100 against all the faces of the package.
- 100 13. In a wrapping machine, an upper horizontal channel having an open end

- across which a vertical wrapper may be located, a lower horizontal channel beneath the upper channel and composed of sections spaced in vertical alignment with the entrance 5 to the upper channel to permit a positioned blank to extend across said lower channel, means for conveying a package into engagement with a wrapper blank located opposite the entrance of the upper channel and 10 thence into said entrance and through the channel to produce an assembly, means for conveying the assembly from the upper channel to the lower channel, means for conveying the assembly through the lower channel, and means operative between the entrance to the upper channel and the exit 15 from the lower channel, for folding the wrapper flatwise against all the faces of the package.
14. In a wrapping machine, wrapper delivery mechanism operative to position an adhesively prepared wrapper blank in the path of a packet to be wrapped, means for conveying the assembled packet and 20 wrapper along the predetermined path, and stationary elements adjacent said path for folding the wrapper about four consecutive faces of the packet, folding projecting marginal wrapper portions against the remaining packet faces to produce wing flaps, and folding said wing flaps flatwise against the said remaining faces of the packet.
15. In a wrapping machine, wrapper delivery mechanism operative to position an adhesively prepared wrapper blank in the path of a packet to be wrapped, a plurality 35 of channels, means for conveying the assembled package and wrapper through the first channel, means for conveying the assembly 40 from the first channel to the second channel, means for conveying the assembly through the second channel, and means forming a part of the said channels operative on the assembly between the entrance to the first channel and the exit from the second channel for folding the wrapper flatwise against all the faces of the package.
16. In a wrapping machine, wrapper delivery mechanism operative to position an adhesively prepared wrapper blank in the path of a packet to be wrapped, means for conveying the assembled packet and wrapper through the first channel, means for conveying the assembly from the first channel to 50 the second channel, means for conveying the assembly through the second channel, and stationary means operative on the assembly between the entrance to the first channel and the exit from the second channel for folding the wrapper flatwise against all the faces of the package.
17. In a wrapping machine, wrapper delivery mechanism operative to position an adhesively prepared wrapper blank in the

path of a packet to be wrapped, a plurality 65 of parallel channels, means for conveying the assembled packet and wrapper through the first channel, means for conveying the assembly from the first channel to the second channel, means for conveying the assembly through the second channel, and means operative on the assembly between the entrance to the first channel and the exit from the second channel for folding the wrapper flatwise against all the faces of the 75 packet.

18. In a wrapping machine, wrapper delivery mechanism operative to position an adhesively prepared wrapper blank in the path of a packet to be wrapped, a plurality 80 of parallel superposed channels, means for conveying the assembled packet and wrapper through the first channel, means for conveying the assembly from the first channel to the second channel, means for conveying the assembly through the second channel, and means operative on the assembly between the entrance to the first channel and the exit from the second channel for folding the wrapper flatwise against all the faces of 85 the packet.

19. In a wrapping machine, wrapper delivery mechanism operative to position an adhesively prepared wrapper blank in the path of a packet to be wrapped, a plurality 90 of parallel channels, means for conveying the assembled packet and wrapper through the first channel in one direction, means for conveying the assembly from the first channel to the second channel, means for conveying the assembly in the opposite direction through the second channel, and means operative on the assembly between the entrance of the first channel and the exit from the second channel for folding the wrapper flatwise against all the faces of 95 the package.

20. In a wrapping machine, wrapper delivery mechanism operative to position an adhesively prepared wrapper blank in the path of the packet to be wrapped, a plurality 100 of parallel channels, plunger means for conveying the assembled package and wrapper through the first channel in one direction, means for conveying the assembly from the first channel to the second channel, plunger means for conveying the assembly in the opposite direction through the second channel, and means operative on the assembly between the entrance to the first channel and the exit from the second channel for folding the wrapper flatwise against 105 all the faces of the package.

21. In a wrapping machine, wrapper delivery mechanism operative to position an adhesively prepared wrapper blank in the path of the packet to be wrapped, a plurality 110 of channels, means for conveying the assembled packet and wrapper through the

first channel, means for conveying the assembly through the second channel, a reciprocated carrier adapted to receive the assembly from the first channel and receive it into operative relation with a means for conveying the assembly to the second channel, and means operative on the assembly between the entrance to the first channel and the exit from the second channel for folding the wrapper flatwise against all the faces 10 of the package.

In testimony whereof I have hereunto set my hand.

HILARIO DE ESCOBALES.
